LAUNDRY MACHINE

Walter K. Voss, Davenport, Iowa

Application December 8, 1932, Serial No. 646,247

15 Claims. (Cl. 68—253)

The invention relates generally to laundry machines and the general aim thereof is to provide such a machine as will have a maximum factor of safety in the operation of the wringer mechanism.

An object of the invention is to provide, in a laundry machine embodying wringer mechanism, novel means for releasing an operative pressure between the wringer rolls and instantaneously discontinuing driven movement of said rolls.

Another object is to provide a novel structure in which an actuator is effective, upon either push or pull movement, to relieve the roll pressure and discontinue the driven movement by breaking the power circuit to the prime mover.

In conjunction with the foregoing, another object is to provide a positive, mechanical connection between the actuator and the circuit breaking device which is releasable instantly upon movement of the actuator, and may not be accidentally nor permanently reestablished prior to the resetting of the pressure release mechanism.

A further object resides in the provision of a laundry machine embodying a wringer having a roll-pressure release mechanism and a circuit breaking device, both of said parts being operable by a single actuator, each requiring separate manipulations or acts on the operator's part to recondition the parts for operation, and having such relationship that placing and holding the circuit breaking device again in operative condition must invariably follow resetting of the release mechanism.

More specifically stated, an object is to provide a wringer having safety release mechanism associated therewith and a circuit breaker in the power circuit to the prime mover, said mechanism including an impact member effective upon movement from a normal "set" position to release the operating pressure on the wringer rolls, said circuit breaker having a part mechanically engageable with said impact member only when said member is in its normal position and spring urged for movement when released from said engagement to break the circuit and to assume a remote position precluding the possibility of accidental reengagement and from which it may only be returned by a positive, intentional act on the part of the operator.

Other objects and advantages will become apparent in the following description and from the accompanying drawings, in which:

Figure 1 is a partially diagrammatic view of a laundry machine embodying the features of the

invention, the wringer mechanism and associated parts being shown in vertical section.

Fig. 2 is a top plan view of the wringer and associated parts.

Fig. 3 is a vertical transverse section through one end of the wringer, taken as indicated by the line 3—3 of Fig. 1.

Fig. 4 is a side elevation of the circuit breaking mechanism on an enlarged scale, the enclosing casing being in section.

Figs. 5 and 6 are side elevational views of wringer mechanisms embodying modified forms of actuators.

Figs. 7 and 8 are end views of the modified forms of wringers shown in Figs. 5 and 6, respectively.

Fig. 9 is a sectional view of the circuit breaking mechanism and is taken along the line 9—9 of Fig. 4.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the drawings a preferred form of laundry machine has been shown merely for illustrative purposes. Laundry machines usually embody, in addition to a wringer mechanism, a tub for washing fluid, an agitator therein and a prime mover or driving motor for the agitator which motor customarily serves to drive the wringer mechanism as well. Of these parts it is deemed necessary, for the purpose of disclosing the present invention, to show only the wringer mechanism, generally indicated at 10 (Fig. 1) and the prime mover which is diagrammatically illustrated at 11 as being an electric motor.

The wringer structure embodies a frame having side stiles 12 and 13 connected by a base 14 and a separable head or cross bar 15 arranged to fit telescopically over the upper ends of the side stiles. In the side stiles, which are channel-shaped, are lower half-bearings 16 resting on fixed pins 17 in support of the ends of a shaft 18 which carries a lower wringer roll 19. Also mounted in the side stiles are upper half-bearings 20 which rest upon the ends of a shaft 21 carrying the upper wringer roll 22. A leaf spring 23 has its ends engaging the upper faces of the

bearings 20 and is carried by a suitable device 24 on the head 15 for tensioning the spring 23 to apply a yielding operating pressure to the rolls 19, 22 through the upper bearings. One of the 5 wringer roll shafts (herein the lower shaft 18) is power driven from the motor 11 through suitable and conventional driving connections which include a shaft 25, a clutch (not shown) mounted in the gear box 26, and a detachable connection 10 27, between the clutch and lower roll shaft 18. The wringer frame, as shown, is rigidly supported by a bracket 28 on the gear box assembly.

For relieving or releasing the operative pressure between the wringer rolls in an emergency, 15 means, usually termed a safety release mechanism, is provided and in the present embodiment the mechanism preferably embodies an actuator for effecting operation of the mechanism and means for preventing return of the actuator to its 20 normal or starting position until the mechanism is manually reconditioned or reset. With particular reference to Figs. 1 and 3, the safety release mechanism in this instance comprises the following arrangement of parts. A quickly 25 detachable interengagement between one end of the head and its corresponding side stile is provided which, in this instance, is in the form of interengaging shoulders 29 on the head 15 and side stile 12 formed by striking out corresponding 30 portions from the respective members. The other end of the head carries a depending latching member 30 in the form of a U-shaped stirrup which is pivotally secured as at 31 to the head and is arranged to extend therefrom down- 35 wardly into the corresponding side stile 13 in embracing relation to the bearings and shafts which are disposed in that stile. The pivotal connection 31 between the latching stirrup 30 and the head preferably includes horizontally 40 elongated slots 32 which permit of a limited horizontal shifting movement of the latching stirrup relative to the head.

The base 33 of the latching stirrup is disposed near the base 14 of the wringer frame and said 45 frame carries a catch device 34 which is movable for engagement with the base of the latching stirrup. The catch device 34 preferably comprises a member of generally U-shaped cross section positioned between the sides of the frame 50 base 14 and pivotally mounted thereon for movement on a horizontal axis by such means as a stud 35 which extends through ears 36 on the frame base and through suitable apertures in the spaced arms of the catch device. The catch 55 device on its upper surface has a pair of transversely aligned hooks 37 fashioned to engage the base 33 of the latching stirrup. The arrangement of the hooks 37 and their relationship to the pivotal axis of the catch device 34 is such 60 that the catch device, of and by itself, is incapable of maintaining a holding engagement with the latching stirrup against an upward force exerted longitudinally of said stirrup. Since such a force is always exerted whenever the parts 65 are assembled and the spring 23 is under tension, means is provided for holding the catch device engaged with the latching stirrup. Thus, one leg of an L-shaped lever 38 is rigidly affixed to the arms of the catch device in such manner 70 that, as may be seen in Fig. 3, the other leg of the lever extends upwardly and externally of the side stile.

Approximately midway between the top and bottom of the side stile is a horizontal rod 39 75 which is preferably of angular cross section and

extends through correspondingly angular apertures in the side walls of the stile and for a substantial distance therebeyond. It is preferred that the rod have a normal central position toward which it is constantly urged by such means as springs 40 of equal tension, each bearing between one side of the stile and a central pin 41 extending transversely through the rod 39. Regardless of the direction in which the rod 39 is moved longitudinally, one or the other of the 10 springs 40 will exert a force for returning the rod to its normal position. The rod 39 carries a finger 42 located externally of the side stile for engagement with the upper end of the lever 38 when the rod is in its normal position. This 15 engagement between the finger 42 and lever 38 is effective to hold the catch device 34 in engagement with the base 33 of the latching stirrup as shown in Fig. 1. If, however, the rod 39 is shifted longitudinally in either direction, the finger 42 is 20 moved out of engagement with the lever 38 whereupon the force exerted by the spring 23 is effective to move the head and the latching stirrup 30 upwardly thereby breaking the engagement between the catch device 34 and the latching 25 stirrup. Once this movement has carried the head above the side stile 13, the head may move horizontally a distance ample to disengage the shoulders 29. These disengaging movements, of course, are practically instantaneous and result 30 in a complete disengagement of the head from the side stiles whereby entirely to relieve the wringer rolls from the pressure exerted by the spring 23.

Means is provided for preventing an accidental 35 return movement of the catch device 34 and lever 38 once the holding engagements of these parts have been broken. In this instance, such means comprises an upwardly extending arm 38^a which is mounted between the spaced arms of the catch 40 device 34 on the lever 38. The arm extends through a suitable aperture 33^a in the base 33 of the latching stirrup. The arm 38^a is of ample 45 length to engage the base 33 in all positions of the latching stirrup relative to the side stile and has an elongated surface 38^b (Fig. 1) fashioned for engagement with the base 33 by which the catch device 34 is held out of latching engagement with the base 33. Opposite the lowermost 50 position assumed by the base of the latching stirrup, the arm is recessed, as at 38^c, to allow the catch device 34 to swing into latched engagement with the base 33. Preferably, the surfaces 38^b and 38^c are connected by a sloping cam-like 55 surface which facilitates movement of the catch device 34 to its inoperative position when the mechanism is tripped. Accordingly, after the holding engagement of the catch device with the locking stirrup has once been interrupted, the catch device 60 must remain in its inoperative position until the head has been reassembled with the side stiles to position the base 33 of the latching stirrup opposite the recess 38^c.

As shown in Figs. 1 to 3, inclusive, reciprocation of the rod 39 to relieve the pressure between the 65 wringer rolls is produced by actuators which are disposed for convenient manipulation by an operator. Only one actuator need be provided, although two, located one on either side of the wringer, are preferable since most wringers are 70 intended and arranged to receive clothes from either side. The preferred form of actuator comprises a U-shaped member 43, the base portion of which extends between the side stiles in parallelism with the wringer rolls and about on the 75

line of the top of the upper wringer roll. The legs of the U extend downwardly along the opposite side stiles and, in this instance, are secured to the wringer frame at their lower ends by means of pivots 44 carried by brackets 45 on the frame. As shown, an actuator is mounted adjacent each side face of the wringer. At each end of the frame, the actuators are connected by such means as bars 46 so that the actuators move conjointly. The ends of the rod 39 are arranged to engage the adjacent side legs of the actuators, as shown in Fig. 3, whereby movement of either actuator toward or away from the frame will shift the rod 39 longitudinally to release the lever 38 and thereby trip the safety release mechanism.

Figs. 5 and 7 and Figs. 6 and 8 show different modified types of actuators for effecting the same result. In Figs. 5 to 7, the U-shaped actuators are indicated at 47 and at either end have upwardly extending rods 48 through which the actuators are pivotally secured to brackets 49 (Fig. 7) located near the top of the wringer frame. As in the first described form, the actuators are preferably connected by bars 50 for conjoint movement. In the form shown in Figs. 6 and 8, the actuators embody U-shaped members 51 rigidly secured together to form a unitary structure by means of upper and lower bars 52 extending between the side arms of the member. The bars are engaged and supported by grooved anti-friction elements 53 whereby the actuator is mounted on the wringer frame for shifting movement relative thereto. In either of the forms shown in Figs. 6 to 8, inclusive, the relationship between the bar 39 and the actuators is such that the operator, by moving an actuator either toward or away from the wringer frame, may relieve the wringer rolls from operative pressure.

An important feature of the present invention resides in the means whereby driven movement of the wringer rolls may be discontinued or interrupted simultaneously with the release of pressure from the wringer rolls. Referring to Figs. 1, 4 and 9, a bracket 54 is rigidly secured to the end of the side stile 13 and supports a casing 55 for a circuit breaking device or switch 56. In a preferred form, the switch comprises spaced terminals 57 and 58, a spanning contact arm 59 and a controlling or operating lever 60. The terminals 57, 58 are preferably mounted near the upper and lower parts of the casing as seen in Fig. 4. The lower terminal 58 is in the form of an elongated rod rigid with an insulating base 61. One end of the contact arm 59 is apertured to receive the terminal rod and at this point is arcuately shaped, as at 62, so that the arm may rock easily over said insulated base. Such means as a spring 63, bearing between a washer 64 on the end of the terminal rod 58 and a loose washer 65 abutting the contact arm, holds the arm against the base and at the same time insures an electrical connection between the terminal and arm.

The other end of the contact arm 59 carries a contact point 66 arranged to engage the terminal 57. The contact arm is normally urged into a circuit breaking position, as shown in Fig. 4. To this end, the lever 60 extends (see Fig. 9) loosely through a central slot in the arm 59 and also, as shown in Fig. 4, extends loosely through elongated slots in opposite walls of the casing 55. Surrounding the lever 60 is a spring 67 which bears between the adjacent wall of the casing and a washer 68 or the like which is mounted on the lever 60 and is held against relative longitudinal movement in one direction by a pin 69

through the lever. The spring 67 exerts a force at all times on the contact 59 tending to separate the point 66 from the terminal 57.

The contact arm 59 is normally urged toward engagement with the other side of the pin 69 by means of a spring 70 which is mounted on the lever 60 and bears between the arm and a pin and washer 71, 72 respectively on the lever 60. The spring 70 allows the contact arm to move relative to the lever 60 after the point 66 has engaged the terminal 57, thereby insuring a perfect spring pressed electrical connection which will not be affected by wear. This arrangement also eliminates the need of an exceedingly accurate adjustment of the parts. The circuit breaker 55 is interposed in the usual manner in the power circuit of the motor 11 as is indicated by the lead lines 71, 72 (Fig. 1).

As may be seen in Fig. 1, the circuit breaker is so mounted on the wringer frame that the swinging movement of the contact arm 59 in breaking the circuit therethrough is in a direction away from the wringer frame. In consequence, the lever 60 in the opening movement of the switch contact will shift longitudinally away from the wringer frame and at the same time, due to the pivoting of the contact arm, the end of the lever 60 nearest the wringer frame will have an upward swinging movement. The circuit breaker is so mounted on the wringer, and particularly with respect to the bar 46 which connects the actuators, that the end of the lever nearest the frame is substantially adjacent to said bar. This end of the lever carries an engaging member such as a hook 73. The bar 46 carries a complementary engaging part also in the nature of a hook 74. The hooks 73 and 74 are both of narrow width and are so related that engagement between the two hooks is possible only when the safety release mechanism is set. Any movement, therefore, of the actuators 43 in either direction will break the engagement between the hooks 73 and 74 to allow circuit breaking movement of the contact arm 59.

In describing the operation of the device, it will be considered that the mechanism is set for operation as shown in Fig. 1. The operator, acting in an emergency, strikes or pulls either one of the actuators 43 thereby moving the rod 39 to release the lever 38 and trip the safety release mechanism. Simultaneously, the hook 74 is carried out of engagement with the hook 73 and the motor circuit is broken. Consequently, not only are the wringer rolls relieved of their operative pressure, but the driven movement of the rolls is instantly discontinued.

An important advantage is obtained by the relationship of the parts after the mechanism has been tripped. Once the connection between the finger 42 and lever 38 has been interrupted, the lever 38 swings in a direction which is transverse to the direction of movement of the rod 39 and across the path of movement of the finger 42. The finger is of substantial width for sidewise engagement with the lever 38 when the lever has so moved. Consequently, since the lever 38 cannot accidentally return to its starting position, because of the relationship between the arm 38a on the catch device 34 and the base 33 of the latching stirrup, the sidewise engagement between the finger 42 and lever 38 is maintained until the wringer elements are returned to or reset in their operating relationship. Hence, after actuation of the safety release mechanism, the hook 74 is positively held at one side or the

other of the position in which it is engageable by the hook 73 on the switch controlling lever 60. Furthermore, the hook 73, upon breaking of the engagement between the hooks 73 and 74, shifts 5 horizontally away and also swings vertically upward away from the only possible position of engagement with the hook 74.

By virtue of these movements, the hooks 73 and 74 are both shifted to a remote position 10 where accidental reengagement thereof is impossible. It will be evident, therefore, that the hook 74 must first be returned to its engageable position by the resetting of the safety release mechanism before the hook 73 may be caused to 15 engage therewith. Moreover, the hook 73 can only be reengaged with the hook 74 by a definite intentional act or manipulation of the control lever 60 by the operator. To facilitate this movement, a finger piece 75 may be provided on the 20 outer end of the lever 60. It should be noted that the operator may, if desired, manipulate the lever 60 independently of the safety release mechanism to break the motor circuit and thereby interrupt the driven movement of the wringer rolls 25 without affecting the setting of the safety release mechanism.

From the foregoing, it will be evident that a laundry machine has been provided which materially increases the operator's factor of safety. 30 By providing actuators for the safety release mechanism which will function upon movement thereof either toward or away from the wringer frame, the operator may instantly relieve the pressure between the wringer rolls and discontinue 35 the driving operation thereof. The actuators are so arranged that it becomes practically impossible for the operator to become entangled in such fashion that the actuators cannot or will not be moved either intentionally or unintentionally. 40 After the safety release mechanism has been tripped, it is impossible for any part to be accidentally returned to an operative position with resulting injury to the operator. Moreover, in resetting the device the sequence of manipulative 45 steps requires the operator to first recondition the wringer rolls for operation before the driving connection to the rolls can be reestablished. Consequently, the operator cannot be injured by an accident resulting from driving the rolls while the 50 wringer is not ready for use.

I claim as my invention:

1. In a laundry machine, the combination of a wringer frame, rolls mounted therein, means for maintaining the rolls under operating pressure, safety release mechanism for relieving such pressure, actuators for said mechanism pivotally connected one to each side of said frame for movement toward and away from said frame and fashioned to extend along at least three sides of 55 the space occupied by said rolls, said actuators being connected together for conjoint movement, a hook movable with said actuators, a prime mover for driving said rolls including a power circuit, a circuit breaker interposed in said circuit, a contact controller having a hook engageable with said first mentioned hook only when the circuit breaker is closed and the actuators are in the position assumed when the rolls are under 60 pressure, spring means tending at all times to move said hook on said controller out of engagement with said first mentioned hook, and means for holding said first mentioned hook out of position for engagement by said hook on said controller as long as the safety release mechanism 65 is inoperative.

2. In a laundry machine, the combination of a wringer frame, rolls mounted therein, means for maintaining the rolls under operating pressure, safety release mechanism for relieving such pressure, connected actuators for said mechanism mounted on opposite sides of said frame for movement toward and away from said frame, engageable means movable with said actuators, a prime mover for driving said rolls including a power circuit, a circuit breaker interposed in said circuit, 10 a contact controller having a part fashioned for connection with said engageable means, spring means tending at all times to move said part out of engagement with said engageable means, and means for holding said engageable means out of 15 position for engagement by said part after said safety release mechanism has been actuated to relieve the pressure on said rolls, whereby the power circuit cannot be permanently reestablished until after the wringer rolls have been placed in 20 operative condition.

3. In a laundry machine, the combination of a wringer frame, rolls mounted therein, means for maintaining the rolls under operating pressure, safety release mechanism for relieving such pressure, an actuator for said mechanism movable toward and away from said frame and fashioned normally to extend in a substantially vertical plane along at least three sides of the space occupied by said rolls when the rolls are under pressure, a prime mover for driving said rolls including a power circuit, a circuit breaker interposed in said circuit, a contact controller having a hook engageable with said actuator only when the circuit breaker is closed and the actuator is in the 30 normal position thereof, spring means tending at all times to move said hook out of engagement with said actuator, and means for holding said actuator out of possible engagement by said hook after actuation of said mechanism and prior to 40 resetting the device for operation.

4. In a laundry machine, the combination of a frame, rolls mounted therein, means for maintaining the rolls under operating pressure, safety release mechanism for relieving such pressure, a 45 movable actuator for said mechanism, a prime mover for driving said rolls including a power circuit, a circuit breaker interposed in said circuit, a contact controller having a part engageable with said actuator to hold the circuit breaker in circuit closing position, and means for holding said actuator out of position for engagement by said part after the safety release mechanism has been operated.

5. In a laundry machine, the combination of a 55 wringer frame, rolls mounted therein, means for maintaining the rolls under operating pressure, safety release mechanism for relieving such pressure, a movable actuator for said mechanism, a prime mover for driving said rolls including a power circuit, a circuit breaker interposed in said circuit, a contact controller having a part engageable with said actuator only when the circuit breaker is closed, and spring means tending at all 60 times to move said part out of engagement with said actuator whereby movement of said actuator releases said contact controller to break said power circuit.

6. A wringer comprising, in combination, a frame, wringer rolls normally maintained under 70 operative pressure, a safety release mechanism for relieving the rolls of such pressure including an actuator moveable relative to said frame, a driving motor having a power circuit, a switch in said circuit including a normally open contact, 75

and means connected with said contact for detachable engagement with said actuator to hold said contact in closed position, said means having a combined shifting and swinging movement when 5 said engagement is broken to a remote position where accidental reengagement with said actuator is impossible.

7. A wringer comprising, in combination, a frame, wringer rolls in said frame normally maintained under operative pressure, mechanism for releasing said pressure from the rolls including an actuator mounted on the side of the frame for transverse movement toward or away from said frame, a driving motor having a power circuit, a 10 switch in said circuit including a contact resiliently urged toward an open position, and means connected with said contact and engageable with said actuator to hold said contact in closed position, said engagement being releasable by said 15 transverse movement of said actuator in either direction, said means having a combined shifting and swinging movement upon disengagement from said actuator to a point where reengagement can only be effected by an intentional manipulation on the part of the operator.

8. A wringer comprising, in combination, a frame, wringer rolls in said frame normally maintained under operative pressure, mechanism for releasing said pressure from the rolls including an actuator mounted on the side of the frame for transverse movement toward or away from said frame, a driving motor having a power circuit and a switch in said circuit comprising a movable contact, resilient means tending at all 30 times to move said contact to its open position, an operating lever connected with said contact having means thereon for detachable engagement with said actuator only when the safety release mechanism is set to allow operative pressure upon the rolls, and an operator's finger piece 35 on said lever.

9. The combination, in a wringer mechanism having rolls normally operating under pressure and means for driving said rolls, of mechanism 40 for relieving such operating pressure, discontinuing means for interrupting the roll drive, and a positive connection between said mechanism and said discontinuing means by which the roll drive is held against interruption only as long as said mechanism is so conditioned that the 45 rolls may be under operative pressure, said connection having separable parts each movable away from the point of engagement when the safety release mechanism is actuated, said parts being reengageable only after the operator has reset said mechanism for operation and positively returned the discontinuing means from the inoperative position thereof in that sequence of manipulative movements.

10. A wringer comprising, in combination, a frame, wringer rolls normally maintained under operative pressure, mechanism for relieving the rolls of such pressure, actuators for said mechanism comprising a U-shaped member disposed 50 on each side of the frame with the base part thereof paralleling the wringer rolls and with the sides extending downwardly along the sides of the wringer frame, means for pivotally securing said members to the frame near the top thereof, means for connecting said members together for conjoint movement, a circuit controlling the operation of the wringer rolls, a switch in said circuit having a normally open contact,

and a disengageable connection between said actuators and said contact for holding said contact in circuit closing position.

11. A wringer comprising, in combination, a frame, wringer rolls normally maintained under operative pressure, a safety release mechanism for relieving the rolls of such pressure, actuators for said mechanism comprising a U-shaped member disposed on each side of the frame with the base of the member paralleling the wringer rolls 10 and the sides thereof extending downwardly along the sides of the wringer frame, means extending between said members across either end of the frame for rigidly connecting said members together for movement as a unit, guides on 15 said frame engaging said means to support said members for movement toward and away from said frame, a circuit controlling the operation of the wringer rolls, a switch in said circuit, and a disengageable connection between said contact 20 and said actuators for maintaining a circuit through said switch.

12. In a wringer, the combination of wringer rolls, quick release means for holding said rolls in operative relation, electric driving means including a control switch, and means manipulable by the operator and independently connected with said quick release means and said control switch for effecting the release of said rolls and opening of said switch together or independently 30 should either element fail to function.

13. In a wringer, the combination of rotatable wringer rolls, quick release mechanism for holding said rolls under operating pressure and operable to release such pressure therefrom, driving 35 mechanism for said rolls, and means operatively connected with driving mechanism and said quick release mechanism for simultaneously actuating both mechanisms under normal conditions, the connection with one mechanism being independent of the connection with the other mechanism to insure of actuation of at least one or the other mechanism under all conditions.

14. In a wringer, the combination of separable frame sections having wringer rolls supported 45 therein and means for applying tension to the rolls when the sections are operatively assembled, quickly releasable means for maintaining assembly of said sections including an impositive latch, a transversely reciprocable member mounted on one of said sections and having a spring urged normal position, means connecting said latch with said member in said normal position thereof to hold said latch operative, means disposed for manipulation by the operator and associated with said reciprocable member to move 50 said member upon a push or pull by the operator for interrupting the connection by which the latch was held operative, a switch, and means for opening said switch as said quick release 55 means is operated to release said sections.

15. The combination, in a wringer mechanism having rolls normally operating under pressure and means for driving said rolls, of a safety release mechanism for relieving such operating 65 pressure, discontinuing means for interrupting the roll drive, and cooperating parts correlated for engagement to connect said mechanism and said discontinuing means only by a manipulative act performed subsequent to the act of conditioning the rolls for the imposition of operating pressure thereon.

WALTER K. VOSS.
